HENRY KALLIO INVENTOR.

BY
Richard B. Owen

ATTORNEY.

UNITED STATES PATENT OFFICE.

HENRY KALLIO, OF PAINSDALE, MICHIGAN.

MINER'S KNIFE.

Application filed April 5, 1920. Serial No. 371,350.

To all whom it may concern:

Be it known that I, HENRY KALLIO, a declarant citizen of the United States (formerly a subject of Finland), residing at 5 Painsdale, in the county of Houghton and State of Michigan, have invented certain new and useful Improvements in Miners' Knives, of which the following is a specification.

10 This invention relates to a tool of the combination type and aims to provide an implement of novel construction embracing a number of tools particularly adapted to the needs of a miner and capable of being 15 employed to good advantage and for a variety of good and useful purposes.

A further object is to provide a combination tool having the characteristics of a 20 pocket knife thus permitting it to be conveniently carried on the person and available for use whenever needed.

An additional object is to provide an implement in which the auxiliary tools are carried by pivotally connected support 25 members, the latter being tensionably adjusted to spring open for immediate use when released and adapted to be manually operated.

With these and other objects in view, the 30 invention may be said generally to reside in the details of construction, combination and arrangement of parts as will be herein-after more fully referred to and pointed out in the accompanying drawings, wherein

35 Figure 1 is a side elevational view of a combination tool constructed in accordance with my invention;

Fig. 2 a bottom plan thereof;

Fig. 3 a side elevational view with one 40 side of a pocket removed to disclose the pivoted punch;

Fig. 4 a side view of the pivoted supporting members;

Fig. 5 is a vertical cross-section taken on 45 line 5—5 of Fig. 3;

Fig. 6 is a view from the opposite side of the pivoted member;

Fig. 7 discloses the knife blade and pocket 50 carried upon the side of the implement illustrated in Fig. 6;

Figs. 8 and 9 are perspectives illustrating the manner in which the support members are fitted together; and

Fig. 10 is a vertical cross-section taken 55 on line 10—10 of Fig. 6.

The invention is constructed primarily of

the two main supporting members or plates 1 and 2 which are similar in construction as shown and are adapted to be placed side to side for relatively lateral movement. 60 Each plate is provided with an opening 3 through which extends a pivot 4 which joins one plate to the other. The free end of each plate is cut away as at 5 to accommodate an offset portion 6 projecting inwardly from the inner face of each plate.

The plate 1 has a bill 7 provided at its free end which is adapted to cooperate with the bill 8 formed on plate 2 to provide cutting jaws having the beveled cutting edges 9 and 10 respectively. The upper edge 9 is convexed while the lower edge 10 is concaved as shown, the two edges adapted to move laterally of each other with their beveled sides outwardly and functioning after the 75 manner of scissors. Between the connected ends of the plates coiled about the pivot 4 is a spring 11, one half of which is adapted to fit into the groove seat 12 of the plate 1 while the other half is accommodated in a 80 similarly formed seat 13 in plate 2. This spring is tensioned so that the arms 14 and 15 tend to spring outwardly from each other, separating plates 1 and 2 when the clasp is released.

This clasp consists of an 85 endless wire loop having side strips respectively enlarged, intermediate their ends, to provide hubs 16 from which the looped ends 17 and 18 extend in right angular relation to each other as shown. The clasp straddles 90 the bill 7 of plate 1 to which it is pivoted as indicated at 19 with the loop 17 projecting outwardly and adapted to be connected to a watch chain, etc., while the loop 18 is adapted to be hooked over the bill 8 of plate 95 2, as may be seen to advantage in Figs. 2 and 3. To enable the loop 18 to better grip the bill 8 the notch 20 is provided in the latter and the pressure of the spring arm 15 tends to force the plate 2 outwardly, 100 thus keeping the notched portion of the bill in engagement with the loop and at the same time providing for a slight play between the edge 10 of the bill and the pivot-carried collar 21, as clearly shown in Fig. 105 10, so that the plate 2 can be moved inward sufficiently to displace the loop from the notch when the plates are to be released.

Thus far described, the invention comprises a pair of scissors or snips, the spring tending to hold the cutters 7 and 8 open as disclosed in Fig. 4. By holding the device in 110

the closed fist with the fingers pressing upwardly against plate 2 and the thumb pressing downwardly against plate 1, the cutters 7 and 8 may be brought together like the blades of a scissors and with a similar cutting effect. It is obvious that this cutting action may be accomplished with as much rapidity or snap as the operator desires, it being governed entirely by the contraction 10 of the thumb and fingers as previously pointed out. These "snips" are useful for cutting fuses, and may obviously be employed for other purposes as well where cutting is necessary.

15 The offsets 6 and 6' carried by the plates 1 and 2 constitute a cap-presser for pressing caps upon fuses and extend inwardly of the inner faces of their respective supporting plates, one above the other, so that when 20 the plates are together, the offset 6 rests upon offset 6' with its outer surface in the plane of the outer face of plate 2 and the outer surface of offset 6' in the plane of the outer face of plate 1. Each offset 25 has provided transversely of its flat meeting face 22 or 22' respectively a concaved depression or groove, as indicated at 23 and 23' which when the offsets are brought into contact by the shutting of the plates form a circular hole of a dimension slightly less than 30 the usual fuse cap. In using the cap compressor the cap is first placed upon the end of the fuse and the plates 1 and 2 then released to permit the offsets to be spread apart and placed one over and one below the 35 cap which may then be compressed upon the fuse by contracting the plates and causing the concaved depressions of the offsets to grip and bear against the cap.

40 In addition to the cap presser the invention embodies a pair of nippers, one on each plate, and these are formed by the inclined walls 24 or 24' of the offsets which as may be seen are inclined outwardly from the 45 nipping edges indicated at 25 and 25'. In the opening and shutting of the plates, these edges just clear the shoulders respectively of the free edges of the plates; and, as shown to advantage in Fig. 4, when it is desired 50 to clip off the end of a wire or other object it may be inserted through either the opening at 25 or the opening at 25' and snapped off as the shoulders are moved inwardly past the edges of the offsets, the space between the 55 inclined walls of the offsets and the adjacent edges of the plates providing a clearing space as indicated at 26 and 26' respectively.

50 Pivoted or otherwise fastened by means of pins 27 to the outside of each plate adjacent one edge is an elongated spring bar 28, the free end of one of said springs is adapted to bear against the tang 29 of a knife blade 30, while the end of the other spring bears against the tang 31 of a punch element 32. 65 Both knife and punch are pivotally support-

ed by the pivot 4, the punch being carried on the outside of the plate 2, and consisting of a tool tapered to a point and useful as a powder puncher or for punching holes in metal, wood, or other material. The 70 knife blade is carried upon the outside of plate 1 and is likewise pivoted at 4; the tang of each tool being cut with a shoulder 33 to abut with the edge of the tensioning spring bar when the tools are respectively swung to open position. Affixed to each spring bar and depending downwardly to overhang the tools on the outside is a side plate 34, and each side plate, together with its supporting 75 bar and the adjacent plate, constitutes a pocket in which the respective tools are housed. Each pocket, it is to be observed, is located in proximity to the pivoted end of the plate and provides an offset appreciably widening the plate at such end so that when 80 the plates are together, the pockets jointly constitute a handle whereby the device can be more readily gripped and handled. Each pocket, moreover, affords gripping means for its individual plate by providing a large 85 area of surface against which the pressure of the thumb and fingers may be exerted for contracting the plates during the manipulation of the device.

90 It is believed that the operation of the invention can be readily understood from the foregoing description, and in connection with its use it needs only to be explained that when the plates are clasped together, the device can be readily used either as a knife or as a punch merely by swinging the required tool to open position, and when it is desired to use either the cutters, cap presser, or nipper, the clasp 18 is simply drawn back to free the plates which automatically 95 spring open ready for use. Although the foregoing may be said to embody the preferred construction of the invention it is to be understood that various changes in respect to shape, size and form, and minor details of construction may be resorted to as 100 fall within the scope of the invention claimed.

105 Having thus described the invention what I claim as new and desire to secure by Letters Patent is:—

110 1. A combination tool including a pair of connected plates pivoted to move laterally of each other, cooperative cutting elements at the free ends of said plates, a transversely 115 grooved offset portion having an inclined face on each plate and adapted to be accommodated in a cut-out portion of its associate plate, said offset portion adapted to be in relative abutment when the said plates 120 are together, so that their grooves are joined to form a circular opening, and their inclined faces providing passages opening inwardly from the opposite edges of the associated plates, a pivoted tool mounted on the 125 130

outside of each plate in proximity to the pivoted end thereof, side plates providing gripping means for said tool, means for tensioning said connected plates to normally 5 spring away from each other, and catch means for releasably holding said connected plates together..

2. A combination tool including a pair of spring-actuated members having scissor-like 10 cutting ends adapted to normally spread apart, a shoulder formed on each member, an offset on each member with an edge adapted to cooperate with the shoulder of the opposite member to provide cutting 15 means, said offsets being provided each with

a groove adapted to meet and form a circular opening with the groove of the other offset when the said plates are together, an auxiliary tool pivoted to the outside of each such member, side plates providing handle 20 means for gripping and operating said pivoted members, and catch means for holding the cutter ends of said members together when the latter are closed.

In testimony whereof I affix my signature 25 in presence of two witnesses.

HENRY KALLIO.
